CLAIM

The ornamental design for a hanger for clothing and accessories, as shown and described.

DESCRIPTION

FIG. 1 is a perspective view showing a new design for a hanger for clothing and accessories

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines consisting of unevenly sized dashes define the boundary of the claim, which extends to the boundary but does not include the boundary; while all other broken line depict portions of the hanger for clothing and accessories that form no part of the claimed design.

1 Claim, 4 Drawing Sheets
